Patented Dec. 15, 1914.

2 SHEETS-SHEET 2.

UNITED STATES PATENT OFFICE.

ARVID EMANUEL KARLBERG AND MARSHALL BIDWELL SARGENT, OF INDIANAPOLIS,
INDIANA, ASSIGNORS TO THE STENOTYPE COMPANY, OF INDIANAPOLIS, INDIANA.

ATTACHMENT FOR TYPE-WRITING MACHINES.

1,121,370.

Specification of Letters Patent. Patented Dec. 15, 1914.

Application filed July 10, 1914. Serial No. 850,276.

To all whom it may concern:

Be it known that we, ARVID EMANUEL KARLBERG and MARSHALL B. SARGENT, citizens of the United States, and residents of Indianapolis, in the county of Marion and State of Indiana, have invented certain new and useful Improvements in Attachments for Type-Writing Machines; and we do hereby declare the following to be a full, clear, and exact description of the invention, such as will enable others skilled in the art to which it appertains to make and use the same.

This invention relates to attachments for typewriting machines and more particularly to rewinding devices for use with stenographic writing machines,—the object of the invention being to provide simple and efficient means which shall be actuated automatically by the operation of the typewriting machine to so rewind the paper strip that the same shall be folded back-and-forth upon itself and thus facilitate the subsequent handling of the strip to read portions of the matter printed thereon or for transcribing such matter.

With this and other objects in view, the invention consists in certain novel features of construction and combinations of parts as hereinafter set forth and pointed out in the claims.

In the accompanying drawings; Figure 1 is a plan view illustrating the application of our improvements; Fig. 2 is a side elevation; Fig. 3 is a perspective view of the device; Fig. 4 is a transverse sectional view on a reduced scale, and Fig. 5 is a sectional view on the line 5—5 of Fig. 1.

1 represents a stenographic machine and 1^a the paper feed devices for the same, such as disclosed in application for patent filed by us on the 7th day of April, 1914, and designated by Serial No. 830,317.

Two arms 2—3 are removably attached to the frame of the machine and project rearwardly therefrom. Between these arms, an oscillatory or rocking folding frame 4 is disposed,—said frame being provided centrally between the ends of one of its sides with a journal 5 mounted in a bearing 6 on the arm 2 and the other side of said frame being provided with a bearing 7 which receives a movable spring-pressed journal 8 mounted in the arm 3. A yielding platform 9 is mounted within the rocking frame

and is normally pressed in an outward direction by springs 10 suitably secured within the frame,—said platform being guided in its movements by means of lugs 11 at its corners moving in slots 12 in the sides of the frame. The rocking frame 4 constitutes a receptacle for the folded paper sheet as the latter is fed from the typewriting machine.

Two bars 13 are mounted to slide in suitable guides 14 at each end of the frame 4, and each of these bars is provided at its outer end with an inverted L-shaped arm 15. The arms 15 carry folding fingers 16 adapted to project into the frame 4 over the platform 9 at the several corners thereof. The folding fingers are made with teeth 17 so that they form racks which mesh with segments 18 pivotally mounted on the frame 4 near the ends thereof, said segments forming the hubs of clamps 19 which operate to hold the paper strip while the folding fingers are being withdrawn from one layer of paper and projected over the next layer, as hereinafter explained.

At each end of the frame 4, one of the pair of sliding bars 13 is connected with one arm of a small lever 20 pivoted between its ends to the end of the frame, and the other arm of this lever is connected, by a link 21, with the other bar 13 of the pair of bars. The first-mentioned bar 13 of the pair of bars is provided with a pin or screw 22, with which one end of a spring 23 is connected, the other end of said spring being attached to a pin or screw 24 on the end of the frame 4. The spring 23 operates to normally project the folding fingers inwardly over the platform and to normally retain the clamps 19 at the outer end of their throw out of the path of the incoming paper strip. L-shaped levers 25 are pivotally mounted on the ends of the frame 4,—the shorter arm of each of said levers normally engaging pin 22 in the frame, while the longer arms of said levers project laterally from the frame, and are adapted to be tripped by rollers 27 on the arm 3, when the frame 4 is turned in one direction or the other, for the purpose of operating the folding fingers 16 and paper clamps 19.

A yoke 28 is secured to the arm 2 and affords a bearing for one end of a shaft 29, the other end of said shaft being mounted in a bearing 30 on the arm 2. Two ratchet

wheels 31—32 are loosely mounted on the shaft 29 and slightly spaced apart. Disks 33 are mounted loosely on this same shaft between the ratchet wheels, and are provided with arms 34—35 respectively, normally projecting in opposite directions beyond the peripheries of the ratchet wheels. One end of rod or bar 36 is pivotally connected with the arm 34 and the other end of this rod or bar is connected with a movable part of the mechanism of the typewriting machine, preferably with the paper feed devices as shown in the drawing. A fixed arm 37 projects at right angles from the rod or bar 36, and to the free end of this arm, one end of a link 38 is pivoted,—the other end of said link being pivotally connected with the arm 35. The rod or bar 36 carries a spring-pressed pawl 39 which engages the ratchet wheel 31 and a spring-pressed pawl 40 is mounted on the link 38 in position to engage the ratchet wheel 32, so that when the rod or bar 36 is reciprocated, the ratchet wheels 31—32 will be rotated, respectively in reverse direction.

A pinion 40^a is secured on the shaft 29 and meshes with a gear wheel 41 secured to the shaft or journal 5 of the rocking frame 4. A clutch 42 is disposed between the pinion 40 and the ratchet wheel 31—one member of said clutch being carried by the pinion and the other member being carried by the ratchet wheel 31. The ratchet wheel 32 is also provided with a clutch member 42^a to coöperate with clutch teeth on one end of a sleeve 43 secured to the shaft 29 within the bearing 30.

The fixed arm 2 is made with a rearward extension 44 on which a shifting lever 45 is pivotally mounted, one end of said lever being bifurcated to embrace the pair of ratchet wheels 31—32 to shift them on the shaft 29 and cause one or the other of said ratchet wheels to be clutched to the shaft. In order to afford extended bearings for the shifting lever against the outer faces of the ratchet wheels, the bifurcated arms of said lever are made with fingers 46 which engage the outer faces of said ratchet wheels. The rearward extension 44 of the arm 2 is provided at its rear end with a tubular portion 47 containing a spring-pressed pin 48 to engage one or another of two notches 49 in the rear end of the shift lever to hold the latter in the position to which it may be shifted. The shifting lever 45 is provided with a forward extension 50 which carries a roller 51 to be engaged by a cam 52 on the rocking frame 4, and a similar roller 53 is carried by the rear portion of the shifting lever to be engaged by a cam 54 on said rocking frame.

The free end portion of the paper strip leaving the feed mechanism of the typewriting machine, is placed on the yielding plat-

form 9 so as to pass under the feeding fingers at one end of the latter, and its free extremity will be held by a spring clip 55 at the other end of said platform. During the oscillation of the paper feed devices of the typewriting machine, motion will be imparted to one of the ratchet wheels and from the latter through the gears to the rocking frame to turn the latter. When the frame 4 makes a half turn, the paper will be folded upon itself, and as said frame approaches the completion of a half turn, the long arm 26 of one of the levers 25 will engage one of the rollers 27 on the arm 3, thus causing the operation of said lever to withdraw the folding fingers 16 at one end of the frame and simultaneously cause the clamps 19 to engage the paper at the same end of the frame. When these operations shall have been performed and during the completion of a half turn of the frame 4, one of the cams (52 or 54) will engage one of the rollers (51 or 53) on the shift lever, thus causing the latter to operate to shift the clutch devices on the shaft 29,—disconnecting one of the ratchet wheels from operative rotation to said shaft and connecting the other ratchet wheel with the latter. Motion will now be imparted from the feed mechanism of the typewriting machine, to turn the frame 4 in the reverse direction. During the first portion of such reverse rotation of the frame 4, the arm 26 of lever 25 will leave the roller 27 on arm 3, and spring 23 will operate the sliding bars 13 to cause the clamps 19 to be withdrawn and the feeding fingers 16 to be simultaneously projected over the layer of paper which the clamps had been engaging. The frame will continue to turn until it shall have made a half revolution when the same operations as above described, will take place (the folding fingers and clamps at the other end of the frame 4 being now operated) and another fold of the paper will have been placed in position in the rocking frame. The oscillations of the rocking frame and the operations above described will continue during the operation of the typewriting machine, and the paper strip will be folded back and forth upon itself on the yielding platform and be thus collected or "re-wound" in the rocking or oscillatory frame.

Various slight changes might be made in the details of construction of our invention without departing from the spirit thereof or limiting its scope and hence we do not wish to restrict ourselves to the precise details herein set forth.

Having fully described our invention what we claim as new and desire to secure by Letters-Patent, is:—

1. The combination with the operating mechanism of a typewriting machine, of an oscillatory frame, means for connecting a

- paper strip with said frame, and means connected with said operating mechanism for turning said frame step-by-step and periodically reversing said turning movement of the frame to fold the paper as it comes from the typewriting machine during the normal operation of the latter.
2. The combination with the operating mechanism of a typewriting machine, of paper folding means, and connections between said operating mechanism and said paper folding means for actuating the latter step-by-step and periodically reversing its direction of movement during the normal operation of the operating mechanism of the typewriting machine to fold a paper strip, on which typewriting has been produced, back and forth in superposed layers.
3. The combination with the operating mechanism of a typewriting machine, of an oscillatory frame, means at respective ends of said frame for engaging a paper strip, and means connecting said operating mechanism with said frame for turning the latter step-by-step and periodically reversing its motion during the normal operation of the operating mechanism of the typewriting machine, whereby said strip will be folded back and forth upon itself when said frame is turned in one direction and then the other during the normal operation of the typewriting machine.
4. The combination with a moving part of a typewriting machine, and rearwardly projecting fixed arms, of an oscillatory frame mounted between said arms, means connecting said movable part with said frame for oscillating it, folding fingers at respective ends of said frame, means coöperative with one of the fixed arms for withdrawing said folding fingers, and spring-actuated means for moving said fingers in the opposite direction.
5. The combination with a moving part of a typewriting machine, and rearwardly projecting fixed arms, of an oscillatory frame mounted between said arms, connections between said moving part and the oscillatory frame for oscillating the latter, folding fingers and clamps at each end of said frame, means connected with said fingers and clamps and coöperative with one of said fixed arms to withdraw the folding fingers and cause the clamps to engage the paper at one end or the other of said frame, and spring-operated means for moving said fingers and clamps in the reverse direction.
6. The combination with a moving part of a typewriting machine and rearwardly projected fixed arms, of an oscillatory frame mounted between said arms, a yielding platform in said frame, connections between said moving part and the oscillatory frame for oscillating the latter, paper engaging devices at respective ends of said frame, means coöperative with one of said fixed arms for actuating the paper engaging means, and springs for moving the paper engaging means in the reverse direction.
7. The combination with fixed supports of an oscillatory frame mounted between said supports, means for oscillating said frame, folding fingers at each end of said frame, paper clamps at each end of said frame, rack-and-pinion connections between the folding fingers and clamps, means coöperative with one of said fixed supports for actuating the folding fingers and clamps simultaneously at one end of the frame or the other, and springs for moving said fingers and clamps in the reverse direction.
8. The combination with fixed supports, of an oscillatory frame mounted between said supports, means for oscillating said frame, folding fingers at respective ends of said frame, paper clamps at respective ends of said frame, spring-actuated devices for projecting the fingers into the frame and simultaneously withdrawing the clamps, and means coöperative with one of said supports and said last-mentioned means for withdrawing the folding fingers and applying the clamps to the paper, at one end or the other of said frame.
9. The combination with a moving part of a typewriting machine, and fixed supports, of an oscillatory frame mounted between said supports, paper engaging means at respective ends, means coöperative with one of said fixed supports and said paper engaging means for controlling the operation of the latter, gearing connected with the oscillatory frame, connections between said gearing and the moving part of the typewriting machine and reversing means for said gearing coöperative with one of said frames for automatically causing reversals of rotation of the latter.
10. The combination with fixed supports, of an oscillatory frame, paper engaging means at respective ends of said frame, means coöperative with one of said fixed supports for controlling the operation of said paper engaging means, a shaft mounted on one of said supports, two ratchet wheels loosely mounted on said shaft, gearing between said shaft and a journal of the oscillatory frame, clutch devices between each of said ratchet wheels and the shaft, a shifting lever engaging said ratchet wheels for shifting the clutch devices, means actuated by the oscillatory frame for shifting said shifting lever, ratchet devices engaging said ratchet wheels, and an operating pitman for actuating said ratchet devices.
11. The combination with a moving part of a typewriting machine and fixed supports, of an oscillatory frame mounted between said supports, paper engaging means at respective ends of said supports, means co-

operative with one of said supports and the paper engaging means for controlling the operation of the latter, a shaft mounted on one of said supports, gearing between said 5 shaft and an oscillatory frame, actuating means for said shaft, clutch devices for reversing said actuating means, a connection between said actuating means and a moving part of the typewriting machine, a shifting lever for said clutch devices, means operative 10 by the oscillatory frame for operating said shifting lever, and a spring-pressed

plunger on one of said fixed supports and engaging said shifting lever to temporarily hold the same in the position to which it 15 may be shifted.

In testimony whereof, we have signed this specification in the presence of two subscribing witnesses.
